UNITED STATES PATENT OFFICE.

JOHN E. S. TAYLOR, OF NEW YORK, N. Y.

APPARATUS FOR REMOVING OBSTRUCTIONS FROM PIPES.

SPECIFICATION forming part of Letters Patent No. 739,120, dated September 15, 1903.

Application filed September 13, 1902. Serial No. 123,837. (No model.)

To all whom it may concern:

Be it known that I, JOHN E. S. TAYLOR, a citizen of the United States, residing at New York, in the county of New York and State of New York, have invented a new and useful Apparatus for Removing Obstructions from Pipes, of which the following is a specification.

This invention relates to means for removing obstructions from the drain-pipes and traps of basins, sinks, bath-tubs, and the like, and is designed to apply fluid-pressure to the drain-pipe, so as to force the obstruction therefrom, and also to stop or close the overflow-pipe, so as to prevent escape of the fluid-pressure through said pipe.

It is furthermore designed to employ compressed air as the agent for removing obstructions and to have the apparatus arranged in compact form, so as to be conveniently applied to the drain-pipe without removing any of the fittings, and also to have the apparatus adjustable, so that the closure may be conveniently applied to the overflow-pipe.

With these and other objects in view the present invention consists in the combination and arrangement of parts, as will be herein after more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the drawings, Figure 1 is a sectional view taken through one end of a bath-tub and the drain and overflow pipes with the present apparatus in position for removing an obstruction therefrom. Fig. 2 is a similar view showing the apparatus applied to a basin or stationary washstand. Fig. 3 is an enlarged longitudinal sectional view of the apparatus. Fig. 4 is a plan view of the adjustable clamp for connecting the overflow-pipe closure to the body of the apparatus. Fig. 5 is a sectional view thereof. Fig. 6 is a detail plan view of the swinging arm which carries the closure for the overflow-pipe.

Like characters of reference designate corresponding parts in all of the figures of the drawings.

In carrying out the present invention I employ a force-pump consisting of a hollow cylinder 1, which is provided at its upper end with a removable closure-cap 2, through which works a plunger-rod 3, provided at its upper end with a handle 4 and at its lower end with a suitable plunger or piston 5. The lower extremity of this pump-cylinder is externally tapered and smooth, as indicated at 6, and above this tapered portion the cylinder is externally screw-threaded for the reception of upper and lower nuts or clamping members 7 and 8, between which is snugly clamped an inverted rubber cup 9, which flares outwardly to a diameter considerably greater than that of the pump-cylinder and is also projected below the lower end thereof. The lower tapered end of the cylinder forms the support for the pump and the inverted cup 7c extends slightly beyond the lower end of the cylinder, whereby when the pump is placed in position the cup will be slightly compressed, as shown in Fig. 2.

Mounted externally upon the pump-cylinder is a clamp member 10, which is in the form of a split ring having its opposite ends formed into circular ears 11 and 12, having central alined perforations for the reception of a winged thumb-screw 13, whereby the clamp may be adjusted to snugly hug the pump-cylinder, so that it may be held at any elevation upon the cylinder. One of the ears—as, for instance, the one designated by the numeral 11—is provided upon its inner face 85 with a circular series of radial sockets or seats 14.

Supported upon the clamp member 10 is a swinging arm 15, the lower end of which is reduced to form a circular knuckle 16, which 9c is adapted to be received between the ears of the clamp and has a central opening for the reception of the thumb-screw or bolt 13. One face of the knuckle 16 is provided with a radial rib or tooth 17, which is adapted to take 95 into any one of the sockets or seats 14 of the ear 11, whereby the arm 15 may be adjusted vertically upon the bolt or screw 13 as a center and then rigidly held at any adjusted position.

At the upper end of the arm 15 there is a rubber cup 18, the back of which is secured

to a disk-shaped plate 19 by means of a screw-threaded fastening 20, which pierces the back of the cup and enters the plate, the latter being provided with a shank or stem 21, which 5 is fitted within a longitudinal bifurcation 22 in the upper end of the arm and held therein by means of a screw-threaded fastening 23, which forms a pivotal connection between the cup and the arm 15.

10 In using the device the tapered lower end of the pump-cylinder is placed in the drain-opening of a bath-tub 24, as indicated in Fig. 1, or a basin 25, as shown in Fig. 2, and forced down, so as to create a suction between the 15 cup 9 and the bottom of the tub or basin, so as to form an air-tight connection between the two. It will here be observed that the lower end of the pump-cylinder is tapered, so as to snugly fit drain-openings of different diameters. After the pump has been fitted to the drain-opening the clamp member 10 is adjusted upon the pump-cylinder and the arm 15 swung in such a position as to permit convenient fitting of the cup 18 to the overflow-opening 26, after which the thumb-screw or bolt 13 is tightened to rigidly hold the clamp upon the pump-cylinder and also rigidly support the arm in its adjusted position. When 20 the pump has thus been placed in position, the handle is manipulated to force air downwardly through the drain-pipe 27, so as to dislodge any obstruction which may be in the trap 28. It will now be understood that the purpose of the cup 18 is to close the upper end 25 of the overflow-pipe 29, so that all of the air will be forced downwardly through the drain-pipe, and hence effectively dislodge any obstructions. During the manipulation of the pump the cylinder is, of course, steadied with one hand and there should be a slight lateral pressure toward the arm 15, so as to hold the cup 18 snugly over the overflow-opening.

When the overflow-opening is at a considerable height above the drain-opening—as, 45 for instance, in a bath-tub—the clamp member 10 is drawn down toward the lower end of the cylinder and the arm 15 swung into an upright position, so as to bring the cup 18 over the overflow, and when applied to a basin, as in Fig. 2, the clamp member is elevated and the arm 15 swung downwardly. By this adjustment of the parts the device 50 may be conveniently accommodated to bathtubs, basins, sinks, &c., without regard to the distance between the drain-opening and the overflow.

A very important advantage of the present device is that it does not require a skilled workman to operate the same, and, moreover, 60 does not necessitate the removal of any of the fittings of the bath-tub, basin, sink, or the like, and it is therefore particularly adapted for domestic use as well as for the use of plumbers.

65 Besides the adjustment of the clamp 10 longitudinally upon the pump-cylinder it is also

rotatably adjustable thereon in an annular direction about the pump.

What I claim is—

1. An apparatus of the character described, 70 comprising a pump having means for connection with a drain-pipe, and flexible means carried by the pump for closing an overflow-opening.

2. An apparatus of the character described, 75 comprising a pump having means for connection with a drain-opening, and pivotally-mounted means adjustable longitudinally upon the pump for closing an overflow-opening. 80

3. An apparatus of the character described, comprising a pump having means for connection with a drain-opening, a clamp adjustable longitudinally upon the pump, and means carried by the clamp for closing an overflow- 85 opening.

4. An apparatus of the character described, comprising a pump having means for connection with a drain-opening, a clamp adjustable longitudinally upon the pump, a vertically- 90 swinging arm having an adjustable pivotal connection with the clamp, and means carried by the arm for closing a drain-opening.

5. An apparatus of the character described, comprising a pump having means for connection with a drain-opening, a clamp adjustable longitudinally upon the pump, and means 95 pivotally carried by the clamp for closing an overflow-opening.

6. An apparatus of the character described, 100 comprising a pump having means for connection with a drain-opening, a clamp adjustable longitudinally upon the pump, a vertically- 105 swinging arm having an adjustable pivotal connection with the clamp, and means pivotally carried by the arm for closing an overflow-opening.

7. An apparatus of the character described, comprising a pump having means for connection with a drain-opening, a clamp adjustably 110 embracing the pump, a vertically-swinging arm having one end fitted between the ends of the clamp, a thumb-screw piercing the ends of the clamp and the arm to bind the clamp upon the pump and also to adjustably connect the arm to the clamp, and means carried by the arm for closing an overflow-opening. 115

8. An apparatus of the character described, comprising a pump having means for connection with a drain-opening, a split clamp adjustably embracing the pump with its opposite ends formed into ears having central alined perforations, the inner face of one of the ears being provided with a series of seats or notches, an arm having one end fitted between the ears and provided with a projection to engage the seats or notches, a fastening piercing the ears and the arm, and means carried by the outer end of the arm for closing an overflow-opening. 125

9. An apparatus of the character described, comprising a pump having means for connec- 130

- tion with a drain-opening, and means for closing an overflow-opening, said means being carried by the pump and adjustable around the latter in an annular direction.
- 5 10. An apparatus of the character described, comprising a pump having means for connection with a drain-opening, and means for closing an overflow-opening, said means being carried by the pump and adjustable longitudinally thereon and also around the same in an annular direction.
- 15 11. An apparatus of the character described, comprising a pump having means for connection with a drain-opening, a clamp which is adjustable longitudinally upon the pump and also around the same in an annular direction, a vertically-swinging arm having an adjustable pivotal connection with the clamp, and means carried by the arm for closing an overflow-opening.
- 20 12. An apparatus of the character described, comprising a pump having means for connection with a drain-opening, and also carrying pivotally-mounted means for closing an overflow-opening, consisting of an elastic cup.
- 25 13. An apparatus of the character described, comprising a pump having means for connection with a drain-opening, a member carried by and adjustable upon the pump, and an elastic cup having its back secured to the member.
- 30 14. An apparatus of the character described, comprising a pump having means for connection with a drain-opening, a member adjustable longitudinally upon the pump, an arm having an adjustable pivotal connection with the member, and an elastic cup having its back provided with a stem which is connected to the outer end of the arm.
- 35 15. An apparatus of the character described, comprising a pump, and an elastic cup flexible from top to bottom and carried by and embracing the discharge end of the pump-cylinder, the latter being projected into the cup and terminated short of the open outer end thereof and forming a support for the pump, whereby the cup will be partially compressed when the device is in use.
- 40 16. An apparatus of the character described, comprising a pump having the discharge end of its cylinder tapered, and an elastic cup flexible from top to bottom and having its back embracing and secured to the cylinder, the tapered end of the latter being projected into the cup and terminating short of the outer end thereof, whereby the cup will be compressed when the pump is placed in position for use.
- 45 17. An apparatus of the character described, comprising a pump having the discharge end of its cylinder externally tapered, and an elastic cup flexible from top to bottom having its back embracing and secured to the cylinder, the tapered end of the latter being projected into the cup and terminated short of the open outer end thereof and forming a support for the pump, whereby the cup will be partially compressed when the pump is placed in position for use.
- 50 18. An apparatus of the character described, comprising a pump having the discharge end of its cylinder externally screw-threaded inwardly from the tapered portion, a pair of clamp-nuts or members fitted to the screw-threaded part of the cylinder, and a cup flexible from top to bottom and having its back embracing the pump-cylinder and clamped between the nuts or members, the tapered end of the cylinder being projected into the cup and terminated short of the outer end thereof and forming a support for the pump, whereby the cup will be partially compressed when the pump is placed in position for use.
- 55 19. In an apparatus of the character described, the combination with a pump-cylinder, of a plunger working therein, a plunger-rod carrying the plunger, a handle connected to the plunger-rod, an elastic cup embracing the discharge end of the pump-cylinder and projected beyond the same, a member carried externally by and adjustable upon the cylinder, a swinging arm having an adjustable pivotal connection with the member, and an elastic cup having its back secured to the swinging arm.

In testimony that I claim the foregoing as my own I have hereto affixed my signature in the presence of two witnesses.
